UNITED STATES PATENT OFFICE.

ISAAC W. COOPER, OF APOLLO, PENNSYLVANIA.

WHIP AND LINE HOLDER.

SPECIFICATION forming part of Letters Patent No. 328,466, dated October 20, 1885.

Application filed July 30, 1885. Serial No. 173,111. (No model.)

To all whom it may concern:

Be it known that I, ISAAC W. COOPER, of Apollo, in the county of Armstrong, State of Pennsylvania, have invented a certain new and Improved Whip and Line Holder; and I do hereby declare the following to be a full and exact description of the same, reference being had to the accompanying drawings, forming part of this specification, in which—

5 Figure 1 is a sectional elevation of my improved whip and line holder. Fig. 2 is a rear elevation of the same. Fig. 3 is a cross section taken on the line $x x$.

10 This invention is an improvement in a combined whip-socket and line-holder; and it consists in a hollow cylinder, A, slotted at the rear and base, provided with a spring, C, and a lever fulcrumed at or near its center.

In the drawings, A represents a cylinder 20 open at the top, provided with a slotted opening, B, commencing near the top, extending downwardly the entire length and along the base to a point near the center, as shown in the drawings at Fig. 1.

25 C represents an ordinary wire spring set in a notch, c, at the top of the slot B, curved inwardly for about the one-half length of the cylinder A, then with a reverse curve to the base, at which place it is wound spirally about a bolt 30 or pin, d, thence carried up, and terminating near the lower end of the lever D.

The cylinder A is also provided with an extension, E, at the top and lugs F at the rear, to which is pivoted or fulcrumed the lever D, 35 said lever bearing against the spring at the bottom and the extension E of the cylinder A at the top.

When the whip is pressed into the socket, the butt or larger end forces the spring back 40 until it has passed the inwardly-curved part of the spring C, at which time the spring assumes its original position. Then forcing the lines or reins between the upper part of the lever D and the extension of the cylinder A 45 will cause the lower end of the lever D to

press the spring, and, acting on the spiral, forces the inwardly-bent portion of the spring C to lock the whip more effectually.

Placing the whip in the socket, and then forcing the lines or reins between the projection or extension on the upper part of the cylinder A and the outwardly-curved end of the lever D, will cause the lower end of the latter to force the spring back and lie close to the side of the cylinder, thus confining the 50 spring in such a manner that the whip cannot be withdrawn without removing the lines.

Having thus described my invention, I claim as new—

1. The combination, with the cylinder A, 60 having the elongated slot and extension E, of the lever D, pivoted to the cylinder, and bearing against the extension E with its upper end, and a spring secured to the cylinder and bearing against the inner lower end of the lever, 65 substantially as described.

2. The combination, with the cylinder A, having the elongated slot and extension E, of a lever, D, pivoted between lugs projecting outwardly from the cylinder, said lever having the bent or curved upper end, and a spring, 70 C, mounted on a pin, d, at the lower end of the cylinder A, and having one of its ends bearing against the lower end of the lever D, and its other end bearing against the upper 75 end of the cylinder, substantially as set forth.

3. In combination with the cylinder A, having a slot commencing near the top, extending downwardly and terminating in the base at or near its center, and a projection or extension, E, a spring, one end of which is placed in a notch, c, immediately above the slot B, curving inwardly thence with a reverse curve and wound spirally about a pin, d, and projecting upwardly, as and for the purpose set 80 forth.

ISAAC W. COOPER.
